UNITED STATES PATENT OFFICE.

AUGUSTUS D. KLABER AND EDWIN AUSTIN COX, OF LONDON, ENGLAND,
ASSIGNORS TO A. B. DICK COMPANY, OF CHICAGO, ILLINOIS, A COR-
PORATION OF ILLINOIS.

DUPLICATING APPARATUS.

No. 831,080.

Specification of Letters Patent.

Patented Sept. 18, 1906.

Application filed September 19, 1905. Serial No. 279,204.

To all whom it may concern:

Be it known that we, AUGUSTUS D. KLA-
BER and EDWIN AUSTIN Cox, subjects of the
King of Great Britain, residing in London,
England, have invented certain new and use-
ful Improvements in Duplicating Apparatus,
of which the following is a specification.

Our invention relates generally to paper-
feeding mechanism designed for use in con-
nection with stencil-printing and other simi-
lar apparatus.

It is adapted particularly for use in con-
nection with duplicating apparatus of the
type employing a rotary drum upon the sur-
face, whereof a waxed sheet in which charac-
ters have previously been cut is secured.

The invention will be described in connec-
tion with apparatus of this type without,
however, intent to limit the same specifically
thereto.

In carrying out the invention we employ,
in conjunction with the rotary drum and under-
lying rotary pressure-roller of a duplicat-
ing apparatus, a feed-board upon which a
paper pile is adapted to be placed. Coact-
ing with the upper surface of such a pile is an
oscillating picker driven, preferably, by the
stencil-carrying drum in such manner as to
feed the uppermost sheet from the pile to the
grip of the drum and the underlying pressure-
roller, such sheet being thereupon fed
through the apparatus and simultaneously
receiving the imprint from the stencil upon
said drum.

The invention is illustrated in the accom-
panying drawings, in which—

Figure 1 is a sectional view of a duplicat-
ing-machine employing our invention, this
section being taken on a line just inside one
of the side members of the supporting-frame.
Fig. 2 is a central vertical section. Fig. 3 is
a detail illustrating certain of the parts
shown in Fig. 2; and Fig. 4 is a sectional view
of a duplicating-machine similar in general
to that shown in Figs. 1, 2, and 3, but illus-
trating a modification hereinafter to be re-
ferred to.

Referring to the drawings, in which similar
letters denote corresponding parts, A design-

nates the base of the machine, upon which is 50
supported the frame of the duplicating appa-
ratus consisting of the side members *a*, hav-
ing cross-rods *a'* *a''* *a'''*. Pivoted at *a'* in the
side members of the frame is the duplicator-
drum *B*, comprising two heads connected by 55
a stencil-carrier of foraminated material, on
which is secured a suitable stencil-sheet.
Said drum may be operated in any suitable
manner—as, for instance, by means of the
pinions *b* *b'* and crank *b''*. 60

C designates the pressure-roller, mounted
in pivoted arms *c* and normally pressed up-
ward into engagement with the periphery of
the drum by means of coil-spring *c'*.

The mechanism thus far described is simi- 65
lar in general characteristics to that of the
duplicating-machine known as the "rotary
neostyle."

D designates a bracket, the lower end
whereof is supported upon one of the side 70
members *a* of the frame. This bracket is
provided at its upper end with a slot *d*, re-
ceiving a pin *d'*, carried by a swinging arm *d''*,
a set-nut *d'''* coacting with the pin *d'* to prop-
erly position said swinging arm *d''*. The rear- 75
ward end of the bar *E* is pivotally mounted
at *e'* upon the upper end of an arm *e''*, the
lower end of said arm being pivoted at *e'''*
upon a rock-shaft journaled in the side mem-
bers *a* of the frame. Said oscillating bar *E*, 80
the arm *e''*, and the swinging arm *d''* may be
actuated in any suitable manner for the pur-
pose hereinafter described—as, for instance,
by means of a sheave *f*, carried by the arm *d''*
and coacting with a cam *F*, carried by one of 85
the heads of the drum *B*, a coil-spring *f'*, ex-
tending between the arm *e''*, and a pin on one
of the side members of the frame, serving to
maintain said sheave and cam in engagement.
The arm *e''* on one side of the machine is du- 90
plicated in a similar arm *e''* at the other side,
and pivotally connected with the upper end
of this is an oscillating bar *E'*, this being a
counterpart of the bar *E*.

G designates the feed-board, adapted to 95
receive the sheet pile *g*. Said feed-board *G*
rests upon the cross-rod *a'* and is held in po-
sition thereon by means of the cleats *g'* *g''*.

Carried by said feed-board upon its upper surface are two guides g^2 , one for each of the oscillating bars $E E'$, said bars operating in slots formed in said guides.

5 H designates a shaft extending between and connecting the forward ends of the oscillating bars $E E'$. If desired, said bars $E E'$ may be provided with a number of orifices h , suitably spaced apart, in which the gripping 10 device (of which the shaft H is part) may be mounted to adapt the machine for feeding sheets of varying length.

Carried by the shaft H is a hanger h' , to the depending portion whereof is secured a 15 plate h^2 , lying normally in a plane parallel with that of the sheet pile. Secured to said plate h^2 is a surface h^3 of gripping material. This surface may take any suitable form—as, for instance, a layer or layers of leather, 20 rubber, or an even more adhesive material, such as gelatin. Also the same may be provided with a series of pin-points h^4 , the ends whereof may project a short distance through the said material. Carried by the shaft H on 25 each side of the gripping device just described is a roller h^5 . Preferably said rollers will be loosely mounted upon said shaft, and said shaft will be capable of turning through a small angle relatively to the bars $E E'$, its 30 movement being limited by an arm h^6 , secured to shaft H and coacting with one or the other of two pins $h' h^7$, carried by one of said bars $E E'$. The purpose of this mechanism is to prevent shaft H from turning to such an 35 extent as to allow plate h^3 , carried thereby, to depart very much from a position of parallelism to the sheet pile, so that when a new pile is placed on the support the plate will assume its proper position without further 40 manipulation by the operator.

The rearward end of the feed-board G is prevented from canting by means of a pin g^3 . Such rearward end is preferably recessed to receive a stop I, carried by a collar i, mounted upon the cross-rod a^3 of the machine-frame, said collar having secured thereto or formed integral therewith an arm i' , the upper end whereof is provided with a sheave i^2 , which projects into the path of travel of a 45 cam i^3 , carried by one of the drum-heads.

The operation of the machine thus described is as follows: The drum B being turned and the coil-spring f' maintaining engagement between the sheave f and the cam 55 F, said cam causes the bars $E E'$ to oscillate backward and forward over the sheet pile laid upon the feed-board G, the gripping device carried by said bars being therefore brought into operative relation with the upper surface of said pile to feed the sheets successively therefrom and between the drum and the pressure-roller C. As the gripping 60 device moves the uppermost sheet is pressed

rearward; but on account of the stop I the same is not permitted to pass beyond such 65 stop, but is buckled or bowed upwardly, as shown in Fig. 1. At this time and during a pause in the movement of the gripping device the cam i^3 and sheave i^2 are brought into action by the continued movement of the 70 drum, with the result that the stop I is moved downward (against the tension of the coil-spring i^4 , connected to the cross-rod a^3 and tending to hold the said stop and the arm i' in the position in which they are shown in Fig. 75 1.) Immediately the stop I is thrown to inoperative position the resiliency of the buckled sheet causes the forward edge thereof to spring forward into the bight of the drum B and pressure-roller C. The moment the 80 sheet is grasped by the drum and pressure-roller the movement thereof through the machine is determined by the movement of said drum and the corresponding movement of the pressure-roller, the operation whereof depends upon said drum. This continued movement of the drum returns the oscillating bars $E E'$ and the gripping device carried thereby to its advanced forward position ready to coact with the next successive 90 sheet on the upper surface of the sheet pile. Before the feed-shoe begins its forward movement the sheet is gripped by the drum and pressure-roller, so that during this movement the sheet is unaffected by the movement of the shoe thereover. Also the shoe turns on shaft H somewhat during the forward movement to lessen the grip of the shoe on the paper.

In Fig. 4 we have illustrated a slight modification of the mechanism shown in Figs. 1, 2, and 3 with respect chiefly to the direction of movement of the oscillating bars (corresponding to the bars $E E'$) and that of the gripping device carried thereby. In Fig. 4 100 the cam L, carried by the drum, coacts with a sheave l , carried by an arm L' , slotted to receive the shaft l' , whereby the drum is mounted upon the frame of the machine. The arm L' is pivotally connected to another 105 arm L^2 , pivoted at l^2 to the machine-frame, a coil-spring l^3 serving to maintain the sheave l in engagement with the cam L. The oscillating bar E^3 is here shown as provided with an upturned end E^4 , pivoted at E^5 , so as to 110 receive oscillatory movement, due to the coaction of a sheave l and cam L. Said oscillating bar E^3 is provided with a recess E^6 , coacting with a support E^7 when said bar is moved to a position permitting such coaction. The forward end of said bar is provided with a gripping device, here shown as a block E^8 , of gelatin or other adhesive material, the same overlying the sheet pile resting upon the feed-board. If desired, the feed-board may be provided with a guide E^9 for 115 120 125

the bars E³, and also, if desired, there may be in this modification of the apparatus, as in the apparatus of Figs. 1, 2, and 3, two of the bars E³ (the same in construction and mounting as that shown in Fig. 4,) the gripping device E⁸ extending between and connecting the forward ends of such bars. The operation of this modification is clearly portrayed in Fig. 4. As the bars E³ are moved forward 5 the coaction of the recesses E⁶ and the pins E⁷ permits the gripping device to drop upon the upper surface of the sheet pile. The rearward movement of said bars elevates the gripping device, the same carrying with it 10 the uppermost sheet of the pile. During the pause which immediately follows the elevation of said device opportunity is given for the sheets other than the uppermost to fall away from such uppermost sheet and resume their position upon the pile. As the bars E³ and gripping device continue their 15 rearward movement actuated by the cam L the uppermost sheet, adhering to the gelatin or other material of the gripping device, is passed toward the drum until its advancing 20 edge is projected between such drum and the pressure-roller which detach the sheet from the gripping device and which operate to print upon the sheet and pass it from the 25 machine in the manner above described.

What we claim, and desire to secure by Letters Patent, is—

1. The combination of a rotary drum, a support for a sheet pile, a movable stop at the end of said support adjacent to said 35 drum, a reciprocating feeding device, and means actuated by the rotation of said drum for moving said device to buckle the top sheet of a pile on said support against said 40 stop and then moving said stop to release said sheet, substantially as described.

2. Duplicating apparatus comprising a rotary drum, a gripping device having oscillatory movement transmitted by said drum, a feed-board underlying said device and adapted 45 to support a sheet pile, a paper-stop and means for throwing the same to inoperative position after said gripping device has buckled a sheet laid upon said feed-board, substantially as described.

3. Duplicating apparatus comprising a rotary drum and a feed-board arranged in a substantially horizontal plane and adapted to support a sheet pile, bars operating in a 55 path substantially parallel with the plane of said feed-board and sheet pile, means controlled by the drum for oscillating said bars, a movable gripping device carried by said bars for coacting with and buckling the uppermost sheet of said sheet pile, a paper-stop 60 movable to operative and inoperative positions and means carried by said drum for throwing said stop to inoperative position

after said device has buckled the uppermost sheet of said sheet pile, substantially as described. 65

4. Duplicating apparatus comprising a rotary drum, a bar and means controlled by said drum for transmitting oscillating movement thereto, a gripping device carried by 70 said bar and movable relatively thereto to carry it into operative and inoperative positions, the operative position of said device permitting the same to buckle the uppermost sheet of a sheet pile to feed the same forward 75 toward said drum, and the inoperative position of said device permitting the same to return to the normal position without influencing the next succeeding sheet of such pile, substantially as described. 80

5. Duplicating apparatus, comprising a rotary drum and a feed-board arranged in a substantially horizontal plane and adapted to support a sheet pile, bars having oscillating movement governed by said drum, and a 85 gripping device carried by said bars and adapted to be rotated by coaction with a sheet pile on said feed-board to carry it to operative position when said bars are moved in one direction and to inoperative position 90 when said bars are moved in the opposite direction, substantially as described.

6. The combination of a rotary drum, a support for a sheet pile, a movable stop at the end of said support adjacent to said 95 drum, a cam on said drum arranged to move said stop, and a feeding device and means for reciprocating the same as said drum is rotated for feeding sheets successively from a pile on said support when said stop has been 100 moved by said cam, said means being arranged to start the feeding movement of said device before said stop is moved, substantially as described.

7. Duplicating apparatus comprising a rotary drum and a feed-board arranged in a substantially horizontal plane and adapted to support a sheet pile, a gripping device coacting with the upper surface of said pile, and having oscillating movement governed by 105 said drum, said gripping device comprising a shaft having limited movement, a hanger depending therefrom, a plate secured to said hanger, gripping material secured to said plate and a roller on either side of said 110 hanger, plate and gripping material.

8. Duplicating apparatus comprising a drum, a feed-board adapted to support a sheet pile, a reciprocating gripper-carrier operated by said drum, a gripper pivotally connected to said carrier, said gripper extending across said support, and a gripping-surface on said gripper the major portion of which, when the gripper is in operative position, lies on the side of the pivotal axis of the gripper 120 toward said drum, substantially as described. 125

- 4
9. Duplicating apparatus comprising a rotary drum and a feed-board adapted to support a sheet pile, bars having oscillating movement governed by said drum, a gripping device carried by said bars the same being operative in one direction of movement of said bars and thrown to inoperative position by the return movement of said bars and a roller for partially supporting said gripping device and said bars upon such return movement, substantially as described.

In witness whereof we have signed this specification in the presence of witnesses.
